Application May 18, 1937, Serial No. 143,340

18 Claims.

(Cl. 38—23)

This invention relates to laundry presses and particularly to laundry presses wherein portions of the work piece or garment which hang from the pressing surface of the work-supporting element are supported in a manner to prevent soiling or wrinkling of the overhanging portions while the portion of the garment on the support is pressed by an upper heated member.

More specifically the invention relates to a laundry press comprising a frame, a heated pressing head adjacent the upper part of the press, a plurality of garment supports hereinafter called bucks, means to move said bucks pivotally from a pressing position to a work-receiving position, and means to apply pressure between the head and the particular buck positioned in pressing relationship thereto, the arrangement being such that while the garment on the loaded buck under the head is being pressed the second buck is in work-receiving position.

The invention may be further summarized as consisting of the construction and combination of parts facilitating the movement of successive bucks into a pressing position whereby the plurality of bucks can be pivotally moved between a loading position and a pressing position adjacent a heated ironing head, the loading positions of the said bucks being substantially the same and being suitably positioned with respect to the normal working position of the operator, thus saving the necessity of the operator moving from one buck to the other.

The invention further consists in an arrangement of parts facilitating the movement of the bucks above and beneath each other from a common loading position to the common pressing position.

The invention further consists in novel control arrangements of the movements of the elements mentioned for the purposes set forth.

Other objects of the invention will be apparent from the accompanying specification and drawings.

Referring to the drawings,

Fig. 1 shows a partial sectional elevation of an embodiment of the invention.

Fig. 2 shows a partial cross sectional view along line 2—2 of Fig. 1.

Fig. 3 shows a partial sectional elevation as in Fig. 1 with bucks passing each other.

Fig. 4 shows a partial sectional elevation as in Fig. 1 with bucks in reversed positions from those shown in Fig. 1.

Fig. 5 shows a partial sectional detail of the buck raising mechanism.

Fig. 6 shows a partial section view of the operating control valve.

Fig. 7 shows partial sectional plan view of the buck raising control mechanism.

In the various figures, frames 1 and 2 resting on a base plate 3 have a top rear cross tie member 4 held in place by bolts 5 and 6. The mid-portion of the cross tie 4 carries a cylinder 7 with upper and lower caps 8 and 9 respectively. Within the cylinder 7 is a piston 10 attached to a rod 11 extending through a coiled spring 12 and through the cylinder lower cap 9 to a steam heated head 13 having a steam connection not shown and a lower work surface 14. The cylinder upper cap 8 is provided with a fluid connection 15 through which fluid is supplied to actuate the piston 10 against the spring 12 so as to carry the pressing head 13 downwardly sufficiently to bring the work surface 14 into pressing engagement with garments supported in a manner now to be described.

Extending crosswise of the frame, adjacent the base plate 3 and mounted in the end frames 1 and 2 there is a shaft 16 which preferably intersects the extension of the axis of cylinder 7. Adjacent the end plates 1 and 2 upstanding arms 17 and 18 operatively connected to shaft 16 support a table 19 on which is mounted a buck 20 having an upper work supporting surface 21. In service this work supporting surface 21 may be provided with a pad or other elements not shown. The co-operating surfaces 14 of the heated head 13 and 21 of the buck 20 are curved to internest, as shown for example in Fig. 1.

Adjacent the inner sides of upstanding arms 17 and 18 are double bearing standards 22 and 23 mounted on the base plate 3. The lower bearings of the standards 22 and 23 support the shaft 16 and their upper bearings support a parallel shaft 24. Adjacent the inner side of one standard 22 a pair of quadrant gears 25 and 26 are attached to the shafts 16 and 24 respectively. These gear connections cause the shafts 16 and 24 to rotate in opposite directions when either of them is actuated. Similar gears, 27 and 28 may be provided adjacent the other standard.

Upstanding from the upper quadrant gears 26 and 28 are cylinders 29 and 29' respectively. Within the cylinders 29 and 29' are pistons attached to piston rods 31 which support the ends of a table 32. On the table 32 is mounted a buck 33 having a work piece supporting surface 34. The curvature of the work supporting surface 34 is the same as that of the previously mentioned work supporting surface 21 of buck 20 and is

adapted to intermittently cooperate with the work pressing surface 14 of the heated head 13. Padding or other covering not shown may be provided on the member 34. Attached to the end frames 1 and 2 are cylinders pivotally mounted as at 35 to the frames. In each cylinder there is a piston attached to one end of a piston rod 38 extending through the free end of the cylinder 36 and terminating in a yoke 39 pivoted on pin 40 on the upright 17 or 18, on the forward side thereof. To eyes 41 on the rear sides of the uprights 17 and 18 are attached extension springs 42, the other ends of which are held to the respective end frames by eyes 43. The springs 42 normally hold the arms 17 and 18 inclined to the rearward so that the members 14 and 21 are in cooperative alignment.

The pivotally mounted cylinders 29-29' which support the buck 33 are preferably so designed as to permit movement of the buck 33 between a work-receiving position such as is shown in Fig. 1 wherein the piston rods 31 are extended, and a position such as is shown in Fig. 3 wherein the piston rods are retracted so that the buck 33 may pass freely beneath the buck 20 as these two work-receiving elements are swung between pressing and work-receiving positions. It will be understood that the work-receiving position of the buck 33 is shown in Fig. 1 as one wherein the piston rods 31 are extended substantially to the same extent as the rods are extended when the buck 33 is in pressing position, as shown in Fig. 4.

To effect the various positionings of the elements thus far described, a source of fluid pressure and means to control its operation at various times and locations will now be described.

Referring particularly to Fig. 1, a fluid supply line 50 as shown with a valve 51 which extends right and left branches 52 and 53 respectively with supply lines 54, 55, 57 and 56 to the pressure control valve 58, buck reciprocating control valve 59, buck swinging control valve 60, and main control valve 61, respectively. The three way control valves 58, 59, 60 and 61 have operating levers 62, 63, 64, 65 respectively, exhaust lines 66, 67, 68, 69 respectively, and operating lines 15, 70, 71 and 72, respectively.

The head control valve 58 is held on the frame by bracket 73 so that the valve operating lever 62 is in operative contact with a piston rod 74 on piston 75 in cylinder 76, held in position on a bracket 77 attached to the frame. The piston is held in the retracted position by a spring 78 and in the advanced position by fluid pressure from line 72 controlled by valve 61. The lower end of the valve lever 62 carries a pivoted extension 79 adapted to swing freely to the right as shown and to act as a lever extension and to cause lever movement to the left when pressure thereon is exerted from the right. The said pressure from the right may be exerted by the tip of a lever 80 pivoted on the frame by pin 81, the lever being normally held to the right of the position shown in Fig. 1 by the spring 82 bearing on the bracket 77. The said pressure from the right may be the result of lever contact with tables 19 or 32 or of pressure on lever extension 80' by rod 83 actuated by fluid supplied through inlet 85 to the cylinder 84. A piston and spring (not shown) mounted in cylinder 84 similar to the mounting in cylinder 76 serve to retract the rod 83. Under certain operating conditions later to be described, by detaching the flexible tube 79 from cylinder 29' and adjusting the tube to the inlet 85, fluid is supplied for the cylinder 84. 75

When the valve lever 62 is swing to the right and the lever 80 is then actuated to the right the lever extension 79 swings sufficiently to permit the lever 80 to pass therebeyond after which the lever extension 79 drops back into position to receive the thrust from the right previously described.

Referring to control valve 59, supported on bracket 86 on the frame, the lower end of the valve lever 63 carries a pivoted extension 87 adapted to swing freely to the right, as illustrated, and to act as a lever extension and to cause lever movement to the left when pressure thereon is exerted from the right. The said pressure from the right is exerted by the tip of a lever 89 mounted on the cylinder 29' as the said tip swings in its arc of travel. The said arc of travel carries the said tip beyond contact with the hinged member 81 and on its reversed movement pressure of the said tip swings the lever extension 87, without moving the valve arm, sufficiently to permit the passage of the tip, after which the extension 87 drops back into pressure receiving position.

The valve operating arm 63 of valve 59 is actuated to the right by a rod 90 mounted (with a piston and spring not shown) in cylinder 91 held by bracket 92 to the frame. The cylinder 91 is supplied by motive fluid from operating pipe 72 controlled by valve 61 and lever 65. The exhaust line 67 from the valve 59 supplies motive fluid to a force plunger 93 (see Fig. 5) in cylinders 94 projecting angularly from the upper ends of cylinders 29-29'. The plunger 93 bears against a lever 95 recessed into the piston rod 31 and hung on pin 96. A spring 97 bearing on the piston recess wall and on the lever 95 tends to force the latter outwardly against the plunger 93 when the piston rod is at the upper limit of its travel and against the inner wall of the cylinder when the piston rod is below said limit. At the upper end of the cylinder a recess is provided in registry with the recess in the piston rod and with the cylinder 94 in which is housed the plunger 93. The base of the recess provides a shoulder 98 against which the lever 95 is swung by spring 97 when the upper limit of travel is reached. With the lever 95 resting on shoulder 98, the piston rod 31 is locked against downward movement, while the plunger 93 contacting the lever 95 is positioned to release the lock when actuated by motive fluid supplied by line 67 to cylinder 94. An exhaust passage 99 from cylinder 94 is provided for the motive fluid which is released thereto by the travel of the plunger 93 in its releasing operation on lever 95.

Referring to the main control valve (shown in detail in Fig. 6 from an extension 65' of lever 65), an extension spring 100 is hung and anchored to the frame. Normally the extension 65' bears upon a plate 101 on the upper end of a piston rod 102 carrying a piston 103 housed in a closed cylinder 104 mounted on the frame. Within the cylinder and normally below the piston is a supply of liquid 104' against which the piston bears in consequence of the pull transmitted from the spring 100. The piston has a small passage 105 thru which the liquid gradually passes into the upper part of the cylinder as the piston under spring pressure gradually descends. This combination acts as a dash pot to co-act with valve 61. The piston is supplied with a valve not shown which accommodates the quick return of the piston to the upper end of the cylinder. The piston rod 102 projects downwardly

through the closed cylinder to contact the free end of a valve arm 106 of a valve 107 in the motive fluid supply line to valve 60. The anchored end of valve arm 106 is held by a spring 108 anchored to the frame. The spring 108 is relatively weaker than spring 100. The force of spring 108 and the resistance of the piston against the liquid 104 are coupled against the relatively heavier spring 100 with the valve 107 open. Inactivity or lack of manual manipulation of lever 65-65' by the operator over a period of time will allow the spring 100 to exert its full measure of operativeness to close the valve 107 and so cut off motive fluid from the buck swinging control valve and cylinder 36 to prevent any scorching of material between the head and buck members.

A bell crank 109 hung on the frame on a pin 110 has laterally extending arms 111 and 112. The forward arm 111 is positioned under the valve operating arm 64 of valve 60 controlling swinging movement of the bucks. The arm 111 may be shortened by removing bolts 111' resulting in the operativeness of bell crank 109 under certain conditions later mentioned. The rod 31 in its downward movement previously mentioned carries table 32 downwardly into contact with valve arm 64 to open the valve 60 and swing the bell crank 109, lowering arm 111 and raising arm 112. Arm 112 is thus positioned to receive the downward thrust of table 32 when it retreats from the pressing position in cooperation with head 14 in a manner later to be described.

Assuming that the mechanism is in the position shown in Fig. 1, that a garment has been pressed on buck 20 and that a garment is positioned on buck 33 for pressing, the operator then manually depresses lever 65 on motive fluid valve 61. Motive fluid is thus released to cylinders 76 and 91. The piston rod 90 associated with cylinder 91 and valve 59 swings the valve arm 63 to release motive fluid from cylinders 29-29' through line 70 to line 67 and thence to plunger 93 which results in the release of stop lever 95 from its seat 98 so that the rod 31 descends with table 32 and buck 33. Meanwhile the motive fluid in line 72 supplied to cylinder 76 actuates rod 74 which swings valve arm 62 to release motive fluid from cylinder 7 through line 15. The operation of the two-way valves 59 and 58 is practically instantaneous with the depression of valve hand lever 65 and upon the release of the latter its return to the exhaust position for cylinders 75 and 91 is assured by action of spring 100. The exhaust of motive fluid from cylinders 76 and 91 results in return of the rods 74 and 90 to their retreated positions ready for action again upon their respective valves. With the release of motive fluid from cylinder 7, spring 12 raises pressing head 13 from contact with buck 20 a distance sufficient to accommodate lateral movement of the buck 20. The further descent of table 32 makes contact with the valve arm 64 and depresses the bell crank arm 111, raises the arm 112, and admits motive fluid to the buck swinging cylinder 36.

The pull generated in the cylinder 36 and imparted to the rod 38, shackle 39, uprights 17 and 18 through shaft 16 and segment gears 27 and 28 and cylinders 29-29' swings the bucks 20 and 21 into exchanged positions. As the cylinders 29-29' move backward the member 89 contacts the hinged valve lever extension 87 at a time such that the resultant operation of the valve 59, the admission of motive fluid into cylinders

29-29' and the raising of table 32 act to clear lateral bell crank arm 112 of contact with the table 32. The continued elevation of the table 32 brings the latter in contact with the hinged lever 80 causing the latter to exert pressure from the right against the hinged valve arm extension 79, thus operating the valve 58 which admits motive fluid to line 15 and cylinder 7 and forces downward the piston 10 and the attached heated head 13 against the buck 33, which is now rigidly held upward by the action of the lever 95 just seated on the shoulder 98 as before described. While the two pressing members are in engagement a garment is placed in position upon the forward buck 20, and then the valve lever 65 is depressed to admit motive fluid from line 56 to line 72. Again as before described, the piston rods 74 and 90 operate valves 58 and 59 respectively to their exhaust positions permitting the spring 12 again to raise head 13 and exhausting motive fluid from cylinder 29 to operate plunger 93 and so release piston rod 31 for downward movement with table 32. The descent of table 32 against bell crank extension 112 operates the bell crank 109 to swing bell crank arm 111 against valve arm 64 to an exhaust position which allows the motive fluid to escape through line 68. Then the spring 42 draws the arms 17-18 rearward and, through the quarter gear connections, moves the cylinders 29-29' forward. As the uprights 17-18 move rearward the arms 88 contact the hinged valve lever extension 87 to exert pressure from the right and position the valve 59 for admission of motive fluid from supply line 55 to line 70 and thence to cylinders 29-29' forcing the members 31 upward until the swinging lever 95 locks at the upper limit of travel to hold the buck 33 in the upper loading position. As the upright 18 swings to the rearward in consequence of pull by spring 42, the table 19 contacts the lever 80 resulting in pressure by the latter from the right against the hinged valve arm extension 79 sufficient to set the valve 58 to admit motive fluid into line 15 and cylinder 7 and so move head 13 against the garment on buck 20. This completes a full cycle of operations by the mechanism.

It is to be noted that the motive fluid lines to the swinging cylinders have the flexibility required to accommodate the movement of such swinging members. In some cases the vertical movement of the buck 33 may be dispensed with. When this method of operation is desired the motive supply line 70 is detached from cylinder 29-29' and attached to connection 85 of cylinder 84 and the bell crank extension 111 is removed by removing bolts 111' which unbalances the bell crank 109 which then settles to rest against bracket 86 on the frame. In this case the automatic operation of the valve arm 64 is replaced by a manually operated lever 64' shown in dotted outline in Fig. 1 connected to the valve 60 in such a manner as to attain the action required from the position shown. When the arm 64' is used, arm 64 is removed so as not to be interfered with by contact with table 32.

Again considering the mechanism as shown in Fig. 1, with the modifications outlined in the above paragraph, the buck 33 is to be considered as lowered and table 32 in close proximity to cylinders 29-29'. With a garment placed on buck 33 in its lowered position the lever 64' is then elevated, after depressing the lever 65, thus admitting motive fluid to the respective valve controller cylinders. The elevation of arm 64',

operating valve 60, admits motive fluid to cylinder 36 which swings buck 33 rearward and buck 20 forward, after the depression of lever 65 admits motive fluid to valve 58, releasing head 13 from buck 20 to allow it to pass. Also depressed lever 65 has operated to shift valve 59 to an exhaust position. As the swinging bucks assume reversed positions, the arms 89 on the cylinders 29-29' contact the hinged valve arm extension 87 and exert pressure from the right sufficient to operate the valve 59 admitting motive fluid from line 55 through repositioned line 70 and connection 85 to cylinder 84 thereby actuating piston rod 83 against lever extension 89'. The lever 80-80' exerts pressure from the right against hinged valve arm extension 79 opening the valve 58 thereby admitting motive fluid to cylinder 12 sufficient to bring head 13 all the day down to the buck 33 in proximity to cylinders 29-29' for the pressing operation. The operation of rod 83 on lever 89' substitutes for the contact of table 32 in the previously described cycle. With the release of the manual operation of the valve arm 65 the arm is rotated by the spring 100 so that the valve exhausts the motive fluid from cylinders 75, 84 and 91 in which rods 74, 83 and 90 respectively are promptly retracted. With the pressing action on buck 33 completed, first the valve lever 65 and then the auxiliary valve lever 64' are depressed. When the lever 65 is depressed, valves 58 and 59 are moved to exhaust position and head 13 is elevated from buck 33. With the head 13 elevated, the lever 64' is then lowered exhausting the cylinder 36 through line 71, whereupon the spring 42 swings the uprights 17-18 to the rear and cylinders 29-29' forwardly. The exhaust thru valve 59 has emptied cylinder 84 by lines 70 and 67 and exit 99. Since the spring 97 and lever 95 are in lowered position the inclined plunger in cylinder 94 occupies a position giving free passage to and from line 67 through exit 99. As the upright 17-18 swings to extreme rearward position arm 88 exerts pressure from the right against the hinged valve arm extension 87 to operate the valve 59 to supply motive fluid to cylinder 84 and so actuate lever 89-89'. In this case there are two forces acting on the lever 80-80', the one just outlined and the previously described contact of table 19, both of which effect the downward movement of the head 13 at the suitable time position.

Now referring to the mechanism positioned as in Fig. 1, after a suitable period of inoperation the mechanism shown in detail in Fig. 6, becomes operative as previously described so that the valve 107 is closed and motive fluid through valve 61 is admitted to cylinders 91 and 75 and retained there until the operator manipulates the valve 61. This tends to hold valves 58 and 59 continuously in exhaust positions until the operator actuates valve 61.

The opening of the exhaust valves 58 and 59 due to inactivity of operator will occur when the bucks are stationary in either of the positions illustrated in Fig. 1 and Fig. 4.

With the valves 58 and 59 in their exhaust positions, the effect is for valve 58 to release motive fluid so that head 13 rises from its co-operating buck whether it may be 20 or 33, and for valve 59 to release motive fluid to the plunger 23 so that the buck 33 settles to its lowermost point of travel. With the bucks and connections in the position as shown in Fig. 1, suppose the safety feature becomes active to shut off valve

107 and exhaust valves 58 and 59. Valve 58 releases head 13. Valve 59 releases lever 95 from seat 98 shown in Fig. 5 resulting in the lowering of the buck 33 and table 32 which would ordinarily operate valve 60 to supply motive fluid to the cylinder 36, resulting in an undesirable movement of the bucks to positions shown in Fig. 4, but the provision of valve 107 which has cut off the motive fluid prevents the movement of the bucks. So all movement remains absent until valve 61 is manipulated.

With the positions of the bucks as shown in Fig. 4 and the valves 58 and 59 open, the steam head 13 is released to an elevated position, buck 33 and table 32 are released to a downward position and table 32 contacts member 112 on bell crank 109 which swings member 111 against valve lever 64 to exhaust cylinder 36. When cylinder 36 is exhausted the spring 42 pulls the bucks back to positions shown in Fig. 1, the table 19 opens valve 58 by pressure on lever 80 and the head 13 is moved against buck 20, after which all motion ceases. The head 13 remains momentarily in contact with buck 20 until the arm 89 swings past the valve arm extension 79 whereupon the air held in cylinder 76 again releases the valve 58 and head 13 is moved upward for safety.

Referring to the supports for the bucks and their tables, it is to be noted that the bucks with their supports respectively constitute inverted, U-shaped yokes having pivots on shafts 16 and 24, positioned to swing one within the other, the inner yoke having extensible and retractable arms, linkages being provided to secure simultaneous swinging of the yokes in opposite directions. The displacement by the buck on the inner yoke to secure the exchange of positions of the bucks between identical forward and rear positions is in a radical direction along the supporting arms of the yoke.

Other variations in the operations of the principal elements by changes in the control locations and connections are contemplated and such as fall within the scope of the following claims are a part of the invention.

I claim:

1. A press of the character described comprising a frame, a pressing head, means to move said head between a retracted, non-pressing position and a lowered position, a plurality of bucks each comprising a work-receiving surface and a table-like surface spaced therefrom and adapted to receive work overhanging from said work-receiving surface, means, pivotally supported for motion about a horizontal axis, for supporting one of said bucks, means, pivotally supported about a horizontal axis, for supporting the other of said bucks, means for moving said one of said bucks between a position in pressing engagement with said head and a work-receiving position and means for alternately moving said other of said bucks between a work-receiving position and a position in pressing engagement with said head, whereby said one buck is in pressing position when said other buck is in work-receiving position, said buck-supporting and said buck-moving means cooperating to at least assist in positioning one of said bucks on a direct line between the other of said bucks and the pivot about which said mounting means swings during the motion of said bucks.

2. A press of the character described comprising a frame, a pressing head, means to move said head between a retracted, non-pressing position

and a lowered position, a plurality of bucks each comprising a work-receiving surface and a table-like surface spaced therefrom and adapted to receive work overhanging from said work-receiving surface, pivotally mounted means for supporting one of said bucks, pivotally mounted means for supporting another of said bucks, and means for moving one of said bucks along a path which has an arcuate portion lying in a vertical plane, between a position in pressing engagement with said head and a work-receiving position, means for simultaneously moving another of said bucks, along a path which has an arcuate portion lying in a vertical plane, between a work-receiving position and a position in pressing engagement with said head, said buck-supporting and said buck-moving means cooperating to at least assist in positioning one of said bucks on a direct line between the other of said bucks and the pivot about which said mounting means swings during the motion of said bucks.

3. A laundry press comprising, in combination, a pressing head, a plurality of bucks, respective supporting means for each buck and permitting motion in a vertical plane about a horizontal axis between a work-receiving position and a pressing position beneath said head, the supporting means for one of said bucks comprising spaced elements, the other of said bucks and the supporting means therefor being adapted to pass directly between said spaced elements and between the buck supported by said elements and said axis as said bucks move from one position to the other position, and means to bring each buck into pressing engagement with said head, the longitudinal side-to-side dimension of said pressing head as it comes into contact with either of said bucks generating a plane at right angles to said vertical plane in which said elements swing.

4. In a laundry press, in combination, a frame, a plurality of bucks, means to move in a vertical plane, one of said bucks back and forth between a work-receiving position and a pressing position while moving in a vertical plane the other of said bucks back and forth between a pressing position and a work-receiving position, means to cause one of said bucks to pass beneath the other of said bucks during said motion, each of said bucks being supported by pivotally mounted means, means associated with the mounting means of that buck which passes beneath the other buck to move said buck between an advanced and a retracted position along its said mounting means, a pressing head supported by said frame, and means to cause said head to pressingly engage each of said bucks.

5. In a laundry press, in combination, a pressing head, a plurality of buck elements, supporting means, means for pivotally mounting said bucks on said supporting means, means for moving, back and forth and oppositely to each other and in a vertical plane, said elements between a pressing position beneath said head and a work-receiving position spaced from said head, means to thrust said head into pressing engagement with whichever buck may be in pressing position, said means for pivotally mounting said bucks being in the same plane with the line with the thrust of said head, one of said bucks being adapted to pass directly between the axis, about which said means for mounting pivot and the other of said bucks as said bucks move between pressing and work-receiving positions.

6. In a press of the character described, in combination, a plurality of bucks, one of said

bucks being pivotally mounted to swing in a vertical plane between a work-receiving position and a pressing position, the other of said bucks being pivotally mounted to swing in a vertical plane between the same pressing position and the same work-receiving position and simultaneously therewith beneath the first-mentioned buck and between it and the axis about which it swings during the movement of said bucks, a pressing head, and means to move said head into pressing engagement with whichever of said bucks may be in pressing position.

7. In a press of the character described, in combination, a pressing head, a work-receiving buck, means to pivot said buck between a position in pressing engagement with said head and a work-receiving position, a second buck, means to pivot said second buck between the same work-receiving position and the same pressing position, means to move said second buck upward and away from the axis about which it swings, means to cause said second buck to pass between said axis and said first buck during the motion of said bucks, and means to move said head into and out of pressing engagement with that buck which is in pressing position.

8. A press of the character described comprising a frame, a pressing head, means to move said head between a retracted, non-pressing position and a lowered position, a plurality of bucks each comprising a work-receiving surface and pivotally mounted means for supporting and pivoting said bucks, means for separately moving each buck between a position in pressing engagement with said head and a work-receiving position, and operating means to cause one of said bucks to pass directly between the other of said bucks and the axis, about which the other of said bucks pivots during the motion of said one of said bucks between said positions.

9. In a laundry press, in combination, a frame, a plurality of bucks, means for moving one of said bucks between a work-receiving position and a pressing position, means for moving another of said bucks, simultaneously with the motion of said one of said bucks, between a pressing position and a work-receiving position, operating means to cause one of said bucks to pass directly beneath the other of said bucks during said motion, a pressing head movable to two positions spaced from each other, the two last-mentioned positions being such that in one said pressing head is in pressing engagement with one of said bucks in its pressing position and in the other said pressing head is in pressing engagement with the said other of said bucks in its said pressing position, and means for so moving said head.

10. In a laundry press, in combination, a frame, a plurality of bucks, elements for supporting one of said bucks and having their ends distal from said one buck spaced from each other, means for supporting said distal ends, said elements being rotatable about said distal ends whereby said one buck is oscillatable about a predetermined axis and between a work-receiving position and a work-pressing position, means for rotating a second of said bucks between work-receiving and work-pressing positions along a predetermined path about a predetermined axis, said path being in part directly between said distal ends and in part directly between said one buck and its first-mentioned axis, a pressing head, and means for pressing said head and whichever buck is in pressing position against each other.

11. In a laundry press, in combination, a frame,

a plurality of bucks, elements for supporting one of said bucks and having their ends distal from said one buck spaced from each other, means for supporting said distal ends, said elements being rotatable about said distal ends whereby said one buck is oscillatable about a predetermined axis and between a work-receiving position and a work-pressing position, means for rotating a second of said bucks between work-receiving and work-pressing positions along a predetermined path about a predetermined axis, said path being in part directly between said distal ends and in part directly between said one buck and its first-mentioned axis, a pressing head, means for pressing said head and whichever buck is in pressing position against each other, and means for automatically moving said one buck toward pressing position and said other buck toward work-receiving position simultaneously.

12. In a laundry press, in combination, a frame, a pressing head supported by said frame, a plurality of bucks, means for pivotally mounting said bucks, means for causing one of said bucks to pivot along a path to and away from a work-receiving position, means for causing another of said bucks to pivot between a work-receiving and a pressing position, operative means for causing said one of said bucks to pass beneath said other of said bucks during said motion, and means for causing said one of said bucks to move from a point on said path toward said pressing head, and means for locking said one of said bucks after said one has so moved toward said pressing head.

13. In a laundry press, in combination, a frame, a pressing head supported by said frame, a plurality of bucks, means for pivotally mounting said bucks, means for causing one of said bucks to pivot along a path, means for causing another of said bucks to pivot between a work-receiving and a pressing position, operative means for causing said one of said bucks to pass beneath said other of said bucks during said motion, and means for causing said one of said bucks to move from a point on said path toward said work-receiving position of said other buck, said pressing position being adjacent said pressing head.

14. In a laundry press, in combination, a frame, a pressing head supported by said frame, a plurality of bucks, means for pivotally mounting said bucks, means for causing one of said bucks to pivot along a path, means for causing another of said bucks to pivot between a work-receiving and a pressing position, operative means for causing said one of said bucks to pass beneath said other of said bucks during said motion, and means for causing said one of said bucks to move from a point on said path toward said pressing position of said other buck.

15. In a laundry press, in combination, a frame, a pressing head supported by said frame, a plurality of bucks, means for pivotally mounting said

bucks, means for causing one of said bucks to pivot along a path, means for causing another of said bucks to pivot between a work-receiving and a pressing position, operative means for causing said one of said bucks to pass beneath said other of said bucks during said motion, means for causing said one of said bucks to move from a point on said path toward said pressing position of said other buck, said pressing position being adjacent said pressing head, and means for causing said one of said bucks to move from a point on said path toward said work-receiving position of said other buck.

16. In a laundry press, in combination, a frame, a plurality of bucks, automatic means for moving said bucks simultaneously and in opposite directions between a forward work-receiving position and a rearward pressing position, means to cause one of said bucks to pass directly beneath the other of said bucks during said motion, pressing-head means supported by said frame, means to cause said pressing-head means to move to engage pressingly whatever one of said bucks is in pressing position, and means for locking each of said bucks in its pressing position before said pressing-head means are moved into engagement therewith.

17. In a laundry press, in combination, a frame, a plurality of bucks, automatic means for moving said bucks simultaneously and in opposite directions between a forward work-receiving position and a rearward pressing position, means to cause one of said bucks to pass directly beneath the other of said bucks during said motion, pressing-head means supported by said frame, means to cause said pressing-head means to move to engage pressingly whatever one of said bucks is in pressing position, means for locking each of said bucks in its pressing position before said pressing-head means are moved into engagement therewith, means to cause said pressing-head means to move to be disengaged from a buck in pressing position, and means for unlocking said buck in pressing position after said pressing-head means are disengaged therefrom.

18. In a laundry press, in combination, a frame, a plurality of bucks, automatic means for moving said bucks simultaneously and in opposite directions between a forward work-receiving position and a rearward pressing position, means to cause one of said bucks to pass directly beneath the other of said bucks during said motion, pressing-head means supported by said frame, means to cause said pressing-head means to move to engage pressingly whatever one of said bucks is in pressing position, and means for rendering inoperative said means which cause the engaging motion of the pressing-head means, whereby a buck may be left in pressing position without being engaged by the pressing-head means.
